UNITED STATES PATENT OFFICE.

RUDOLPH RAINALTER, OF ST. JOSEPH, MISSOURI.

MOTOR FOR WASHING-MACHINES, &c.

No. 895,299.

Specification of Letters Patent.

Patented Aug. 4, 1908.

Application filed April 29, 1907. Serial No. 370,929.

To all whom it may concern:

Be it known that I, RUDOLPH RAINALTER, a citizen of the United States, residing at St. Joseph, in the county of Buchanan and State of Missouri, have invented certain new and useful Improvements in Motors for Washing-Machines, &c., of which the following is a specification.

This invention relates to a motor for washing machines &c.; and my objects are to provide a machine of this character which shall have ample power to properly perform its work, which is simple in construction so that it will not require the attention of a skilled mechanic, and one that may be produced at comparatively small cost.

In order that the invention may be fully understood, reference will now be made to the accompanying drawings, in which:—

20 Figure 1 represents an elevation, partly in section, of the machine. Figs. 2 and 3 are cross sections of the motor taken on lines II and III, respectively, of Fig. 5. Fig. 4 is a broken plan view of an agitator and its 25 drive shaft, the latter being in cross section on line IV—IV of Fig. 5. Fig. 5 is an enlarged vertical section of the motor and the agitator on line V—V of Fig. 6. Fig. 6 is a horizontal section on line VI—VI of Fig. 5.

30 For convenience in illustrating the invention I have shown it applied to a wash-tub 1, which is normally closed by a lid 2.

35 3 designates an agitator for stirring the clothes and agitating the water so that it will be forced through the clothes and thus thoroughly cleanse the same. Said agitator is adjustably mounted upon a vertical drive shaft 4, so that it may slide up or down thereon, and thus accommodate itself to the 40 quantity of clothes within the tub. Said agitator is provided with an elongated socket 5, having oppositely-disposed recesses 6 for the reception of a pair of lugs 7 at the lower end of the drive shaft. This

45 arrangement permits the agitator to slide up or down upon the shaft and yet be rotated thereby. The downward movement of the agitator is limited by a set-screw 8 in the upper end of the socket, which is adapted 50 to engage one of the lugs 7.

55 Socket 5 is provided with a plurality of threaded openings 9 arranged at various heights for the reception of the set-screw, so that the vertical adjustment of the agitator may be regulated as desired. For instance, if the tub is shallow the set-screw is placed

in one of the lower openings to shorten the downward movement of the agitator, and when the tub is deep the agitator is permitted to drop further down by placing the set-screw in an upper opening.

Shaft 4 is journaled at its upper portion in ball-bearings 10 arranged in a housing 11.

12 designates a pinion detachably secured to the drive shaft by a pin 13, so that said shaft may be removed from its bearing when desired by withdrawing said pin. Pinion 12 is rotated in reverse directions by a reciprocating rack-bar 14, extending through the housing and held in engagement with pinion 12 by an antifriction roller 15, journaled in the housing.

Rack-bar 14 is removably secured at one end to a piston-head 16 forming part of a reciprocating motor, whereby the machine is operated. Said motor is driven by fluid pressure, water being preferably employed on account of the convenience with which the motor may be connected to a faucet. In constructing said motor I employ a centrally-disposed cylinder-head 17 to which a pair of oppositely-disposed cylinders 18 19 are removably secured, said cylinders being open at their outer ends and closed at their adjacent ends by head 17. Head 17 is provided with oppositely-disposed inlet and exhaust ports 20 21, having externally threaded walls 22 23, respectively, of proper size to receive standard couplings so that inlet 20 may be connected by hose (not shown) to a faucet, and the exhaust connected by a hose (not shown) for the purpose of conducting the used fluid to the tub or other desired point.

95 Inlet 20 communicates with a chamber 24 which in turn communicates with two oppositely-disposed channels 25 26, extending through head 17 and communicating with cylinders 18 19, respectively. Exhaust port 21 communicates with a chamber 27 also arranged within head 17 and communicating with cylinders 18 19 by two oppositely-disposed channels 28 29 respectively. Communication between chamber 24 and channels 25 26 is alternately controlled by an inlet valve 30 extending therethrough, said inlet valve being provided with a centrally-disposed disk 31 and a pair of oppositely-disposed stems 32 33, extending through a pair of yokes 34 35, provided with a pair of centrally-disposed buffers 36 37, respectively.

110 The flow of water through channels 28 29

is controlled by an exhaust valve 38 extending therethrough and provided near its opposite ends with a pair of disks 39 40 for alternately closing their respective channels.

5 Valve 38 is provided with a pair of oppositely-disposed stems 41 42, extending loosely through yokes 34 35, respectively.

43 44 designate a pair of expansion springs interposed between the ends of valve 38 and 10 yokes 34 35, respectively, for the purpose of normally holding said yokes against the headed ends of stems 32 33.

45 46 designate a pair of expansion springs interposed between the ends of valve 38 and 15 yokes 34 35, for the purpose of normally holding the same against the headed ends of stems 41 42.

47 designates a piston-rod, one end of which carries the piston-head 16, while its 20 opposite end carries a duplicate piston-head 48, reciprocably arranged in cylinders 18 19, respectively. The piston-rod 47 is provided at its opposite sides with stuffing-boxes 49 to prevent leakage of the motive fluid from one 25 cylinder to the other.

The motor is supported by a pair of feet 50 and a frame 51, to which latter the former is secured by screws and retaining-nuts 52 53, respectively. Frame 51 is removably secured to lid 2 in any suitable manner and has a duct 54 extending beneath the entire length of the motor, and communicating at its discharge end 55 with the interior of the tub, so that should the motor leak, the fluid therefrom will be conducted to the tub.

When the motor is not in use during cold weather I drain the fluid therefrom so that it will not freeze therein, through a passage-way 56 leading from cylinders 18 19 and communicating with an outlet 57 controlled by a valve 58.

If motive fluid is admitted to chamber 24 while the piston-heads are in the position shown in Fig. 6, said fluid will enter cylinder 45 18 through channel 25 and force piston-head 16 to the end of its outward stroke. As the piston-heads are connected, this movement of head 16 will draw head 48 into contact with buffer 37 and through the instrumentality of the intervening parts move valves 30 38 to the left, so that disks 31 40 will close channels 25 29, respectively. The closing of channel 25 will cause the fluid to enter cylinder 19 through channel 26, and force piston-head 48 to the end of its outward stroke, see Figs. 5 and 6. This movement of piston-head 48 will carry the piston-head 16 to the

right until it contacts with buffer 36 and, through the instrumentality of the intervening parts, move valves 30 and 38 to the left 60 and cause them to open up communication between chambers 24 27 and channels 25 28, respectively. When the piston-head 16 moves to the right as above described, it will force the fluid from cylinder 18 through channel 28, through which it flows to chamber 27, and thence out through the exhaust port 21.

From the above description it will be understood, that the cylinders are alternately charged with a fresh supply of motive fluid, 70 while the used fluid is being alternately discharged from said cylinders. The reciprocatory motion of the piston will be communicated to the rack-bar 14, which will, through the instrumentality of the intervening parts, 75 rotate the agitator first in one direction and then the other.

Having thus described my invention, what I claim is:—

1. A motor of the type set forth embodying a frame formed with a longitudinal inclined duct on its top face and with a vertical discharge passage at one end communicating with the lowest point of said duct, a cylinder head, feet carried by said head secured to central points along the length of said frame on opposite sides of said duct, cylinders carried by said head, pistons in said cylinders and inlet and exhaust valves for said pistons, a piston rod connected to said pistons, a rack bar connected to the piston, an operating shaft passed through said discharge passage of said frame, and a pinion on said shaft in mesh with said rack.

2. A motor embodying a frame having a longitudinal duct therein, a cylinder head secured to said frame and overlying said duct, cylinders on opposite sides of said head, connected pistons in said cylinders, inlet and exhaust valves for said pistons, and means to drain the water from each of said cylinders consisting of a passage-way extending through said cylinder head so as to communicate with each of the cylinders, and an outlet formed in said cylinder head at an intermediate point so as to communicate with said duct, and a valve for the outlet threaded in one of the walls of said cylinder head.

In testimony whereof I affix my signature, in the presence of two witnesses.

RUDOLPH RAINALTER.
